US0D1059567S

(12) **United States Design Patent** (10) **Patent No.:** **US D1,059,567 S**
(45) **Date of Patent:** **** Jan. 28, 2025**

(54) **SCENT DISPENSER**

(71) Applicant: **Arizona Air-Scent, Inc.**, Scottsdale, AZ (US)

(72) Inventor: **Sam Habbel**, Scottsdale, AZ (US)

(73) Assignee: **Arizona Air-Scent, Inc.**, Scottsdale, AZ (US)

(**) Term: **15 Years**

(21) Appl. No.: **29/953,029**

(22) Filed: **Jul. 18, 2024**

Related U.S. Application Data

(62) Division of application No. 29/867,584, filed on Oct. 28, 2022, now Pat. No. Des. 1,039,122.

(57) **CLAIM**

The ornamental design for a scent dispenser, as shown and described.

DESCRIPTION

FIG. 1 is a front perspective view of a design for a scent dispenser;

FIG. 2 is a front view thereof;

FIG. 3 is a rear view thereof;

FIG. 4 is a left side view thereof;

FIG. 5 is a right view thereof;

FIG. 6 is a top view thereof; and,

FIG. 7 is a bottom view thereof.

The broken lines shown in the figures are for the purpose of illustrating portions of the scent dispenser and form no part of the claimed design.

1 Claim, 7 Drawing Sheets
